Primary Examiner — Catherine Tuttle(74) *Attorney, Agent, or Firm* — Blake P. Hurt(57) **CLAIM**

The ornamental design for a bocce ball retriever, as shown and described.

DESCRIPTION

FIG. 1 is a top, front, left side perspective view of a bocce ball retriever showing my new design;

FIG. 2 is a front elevational view thereof;

FIG. 3 is a left side elevational view thereof, the right side elevational view being a mirror image thereof;

FIG. 4 is a rear elevational view thereof;

FIG. 5 is a top plan view thereof; and,

FIG. 6 is a bottom plan view thereof.

The broken lines in FIG. 1 represent environmental structure and form no part of the claimed design.

1 Claim, 3 Drawing Sheets(56)
